UNITED STATES PATENT OFFICE.

DAVID F. CRAWFORD, OF PITTSBURGH, PENNSYLVANIA.

STOKER.

1,119,927.

Specification of Letters Patent.

Patented Dec. 8, 1914.

Application filed April 3, 1909. Serial No. 487,615.

To all whom it may concern:

Be it known that I, DAVID F. CRAWFORD, a citizen of the United States, residing at Pittsburgh, in the county of Allegheny and 5 State of Pennsylvania, have invented certain new and useful Improvements in Stokers, of which the following is a specification.

The invention relates to automatic stokers of the underfeed type and particularly 10 to the trough and feed mechanism. The invention has for its principal objects; the provision of an improved form of step-by-step feed adapted to give a more positive and effective feed than the devices of this 15 character heretofore employed; the provision of an improved form of feed trough constructed to permit a supply of air to be forced therethrough in order to promote combustion of the fuel above the trough; 20 and the provision of improved means for supplying fuel to the end of the feed trough. One embodiment of the invention is illustrated in the accompanying drawings, wherein—

25 Figure 1 is a partial horizontal section taken above the grates.

Figure 2 is a vertical longitudinal section through the center of one of the feed troughs.

30 Figure 3 is an enlarged detail section taken through the center of one of the feed troughs, and

Figure 4 is a longitudinal horizontal section taken through the upper end of the connecting rods of Figure 3, and showing such rods in plan view.

The stoker is illustrated as applied to a locomotive fire-box, but it will be understood that the construction is of general application and not limited to use in the relation shown. Only so much of the fire-box is shown as is necessary to illustrate the relation of the parts.

Referring first to the general arrangement 45 of parts as shown in Figures 1 and 2, the principal parts may be enumerated as follows; 1 is the fire-box, which may be of any approved type; 2 and 3 are the feed troughs extending longitudinally through the furnace; 4 and 5 are hoppers or receptacles from which the fuel is fed or supplied to the rear ends of the feed troughs 2 and 3; 6 and 7 are the side grates located upon the outer sides of the troughs 2 and 3; 8 is the 50 center grate located intermediate the troughs 2 and 3; 9 and 10 are drop grates extending

across the front end of the furnace; 11 is an operating shaft from which the members of the feed mechanism are operated in a manner to be hereinafter described; and 12 is a 60 steam cylinder for oscillating the shaft 11 back and forth and connected thereto by means of the crank 13 upon the shaft 11, a connecting-rod 14 secured to the end of the crank, and the hollow piston 15 in which the 65 connecting rod is pivoted.

The grates 6, 7 and 8 are substantially similar in construction and comprise a series of bars 16 mounted for oscillation, and provided with oppositely projecting fingers 70 17. Each of these brace bars is provided at its end with a downwardly projecting arm 18 (Fig. 2), and the ends of these arms are connected to longitudinally extending bars 19, and each series of braces may be agitated 75 by means of the usual connections extending to the rear of the furnace.

Two feed troughs 2 and 3 are provided, which troughs are the same in construction so that a description of one will suffice for 80 both. As indicated in Figure 3, the trough is provided upon its bottom with a series of transverse truncated ridges 20, 21 and 22, and the members 23, 24, 25 and 26 are provided for feeding the fuel upward and forward from between the depressions intermediate the ridges. Another similar feed member 27 is provided in the inclined bottom of the hopper 4, which member feeds the fuel from the hopper to the end of the 90 trough. The means for operating the various feed members from the shaft 11 will be seen by reference to Figs. 3 and 4. As indicated in the latter Figure each of the feed members is provided with a pair of 95 spaced lugs at its lower edge, and a bearing pin extending between the lugs to which the various connecting rods may be pivoted. The member 25 is operated directly from the crank arm 28 by means of the connecting rod 29, and the members 26 and 23 are operated in unison with the member 25 by means of the pairs of connecting links 30 and 31. The member 24 is operated from a pair of cranks 32 (Fig. 3) by means of the 105 connecting rod 33, whose forked end embraces the cranks 32. The member 27 is also operated from the pair of cranks 32 by means of the connecting rod 34 whose lower end is pivoted between the ends of the 110 cranks 32. The provision of the transverse ridges 20, 21 and 22 reduces the tendency

of the coal at the surface of the trough to cake as the ridges promote an upward feed of the fuel through the trough. The arrangement involving the ridges with the oppositely inclined walls with the feed members between the ridges is advantageous, as the coal passing over the crest of a ridge is directed down the inclined rear face of the ridge and on to a feed member there being no dead space for the collection of fuel when the feed members are in the position of the members 25 and 26 in Fig. 2. It will be noted that the feed members 27, 23, 24 and 25 act in alternation, which arrangement is also advantageous in that a feed member in advance of another feed member is positioned to receive the coal fed forward by the preceding member, and the operation is much more effective and positive than is the case where the feed members are all similarly positioned and act in unison. The two forward feed members 25 and 26 are arranged to act in unison as the rapid forward feed of the fuel is not as necessary at this point as at a point farther back in the trough. The combined arrangement of transverse ridges and feed members serves to keep the mass of fuel in the trough well loosened up, and feeds it upwardly and forwardly in such an effective and uniform manner that little or no hand-firing is necessary. The truncating of the ridges 20, 21 and 22 provides air spaces 36 through which air from the ash pit is forced, thus serving still further to agitate the mass of material in the trough, and promote the coking and combustion of the coal at the surface of the trough. The provision of the feed member 27 in the hopper 4 insures a proper delivery of fuel to the end of the trough, and relieves the fireman of the necessity of forcing the

fuel forwardly, the only manual attention necessary being the maintenance of a proper amount of fuel in the hopper. The downward inclination of the floor of the hopper 45 also assists in securing a proper forward feed.

Having thus described my invention and illustrated its use, what I claim as new and desire to secure by Letters Patent is the following:—

1. In an underfeed stoker, a feed trough provided with a series of transverse ridges each comprising a pair of oppositely inclined walls, a series of movable feed members between the ridges for feeding the fuel upwardly and forwardly from the depressions between the ridges, and means for operating the said members. 55
2. In an underfeed stoker, a feed trough 60 provided with a series of transverse truncated ridges having air passages through their cut off portions and each comprising a pair of oppositely inclined walls, and means between the ridges for feeding fuel through 65 the trough.
3. In an underfeed stoker, a feed trough provided with a series of transverse ridges, each comprising a pair of oppositely inclined walls, movable feed sectors between 70 the ridges for feeding the fuel upwardly and forwardly from the depressions between the ridges, and means for operating the feed sectors pivoted adjacent the outer peripheries of the sectors. 75

In testimony whereof I have hereunto signed my name in the presence of the two subscribed witnesses.

DAVID F. CRAWFORD.
